UNITED STATES PATENT OFFICE.

RALPH A. NELSON AND ANTON PRASIL, OF BUFFALO, NEW YORK, ASSIGNEES TO NATIONAL ANILINE & CHEMICAL COMPANY, INC., OF NEW YORK, N. Y., A CORPORATION OF NEW YORK.

REDUCTION OF NITRO COMPOUNDS.

No Drawing.

Application filed June 22, 1920. Serial No. 390,885.

This invention relates to improvements in the reduction of nitro compounds, and more particularly to the reduction of nitro compounds to hydrazo compounds, by means of zinc and caustic alkali as the reducing agents. The invention also relates to improvements in the separation and isolation of the hydrazo compounds, at the end of the reduction. The invention includes improvements in the reduction operation, in the extraction and isolation operation, and in the combined reduction and isolation operations.

The present invention is based upon the discovery that the reduction of nitro compounds to hydrazo compounds by means of zinc and caustic alkali can be carried out with advantage with the aid of an organic solvent immiscible with water, such as benzene, toluene, etc., so that there is directly produced, as the result of the reduction, a solution of the hydrazo compounds in the immiscible solvent in admixture with the zinc residue. By carrying out the reduction in this way the disadvantages and objections resulting from the reduction as heretofore carried out are overcome or very greatly reduced, so that the hydrazo compounds can be produced with good yield.

In the preferred practice of the invention, the nitro compound in solution in benzene or other solvent, is subjected to reduction by means of zinc and caustic alkali, and the zinc and caustic alkali are intermittently added, and the reaction is controlled by the regulated addition of these reducing agents.

In its broader aspects, the invention includes the carrying out of the reduction with zinc and caustic alkali, regardless of the manner in which they are added, but it is particularly advantageous, in order to secure effective control of the reaction, to add the zinc and caustic both intermittently and progressively so that any considerable accumulation of the reagents is avoided, with the avoidance of the possibility of their suddenly taking hold and causing the reaction to proceed with explosive violence. The gradual and intermittent addition of the zinc and caustic also makes possible the regulation of the reduction in such a way that it may be stopped at the azoxy or azo

stage, while it also makes possible the continuation of the reduction to the hydrazo stage, with substantial completion and without objectional over-reduction to the amido compounds.

It is characteristic of the present invention that there is very little water present, and the reduction is actually carried out in the benzene solution, so that there is no difficulty due to separation of crystals during the reduction. Difficulties due to the presence of excess water are thus avoided, as well as difficulties due to the separation of crystals in admixture with the zinc residue. However, it should be borne in mind that it is essential to have a small amount of water present in order that a complete reduction may be effected.

It is a further characteristic of the invention that the reduction can be carried out at a relatively low temperature, particularly when benzene or toluene are used as a solvent, since, by using a reflux and carrying out the reaction under refluxing conditions the working temperature of the reduction is substantially that of the boiling point of the solvent. Higher boiling solvents can also be used, if the temperature is so controlled that it does not exceed the low temperatures at which but little by-products are formed. The higher temperatures of higher boiling solvents are in general undesirable as they favor the formation of a larger amount of by-products. The best solvent is benzene, owing to its low boiling-point which allows an easy control for carrying out the reduction at a low temperature, and also to its increased solvent action upon the hydrazo compounds.

At the end of the reduction, the hydrazo compound is contained in solution in the hot solvent and this solution is in admixture with the zinc residue. By driving off the solvent, the zinc residue and the hydrazo compound can be directly obtained in admixture, but it is more advantageous to separate the solution of the hydrazo compound from the zinc residue. If the amount of solvent used is not sufficient for complete extraction of the hydrazo compound a further amount of solvent can be added sufficient for the complete solution and extraction, or the extraction can be carried out in stages by separating the solution present at

the end of the reduction and subsequently adding further amounts of the solvent to complete the extraction. Owing to the absence of any substantial amount of water, the zinc residue is in a form well adapted for the separation therefrom of the solution and for the extraction of the hydrazo compound in case it is not entirely in solution.

Where the same solvent is used during the reduction of the nitro compounds to hydrazo compounds and for the separation of the hydrazo compounds from the zinc residue, there is avoided the added operation incident to the use of a different solvent for the reduction and extraction, and the solution of hydrazo compound can be directly produced at the end of the reduction. This solution of hydrazo compound can be readily separated from the zinc residue and the hydrazo obtained in an isolated state free from zinc, while the zinc residue itself can likewise be obtained substantially free from organic matter, and directly available for use without calcination or further treatment, for special purposes.

It will thus be seen that the process of the present invention, in its entirety, involves the reduction of the nitro compound in the presence of the immiscible solvent, and the extraction and recovery of the hydrazo compound from the zinc residue by the immiscible solvent, thus obtaining in a simple and advantageous manner a solution of the hydrazo compound in a state of high purity and with excellent yield, while leaving the zinc residue in an isolated state. It will also be seen that the various steps of the process, as well as the process in its entirety, present features of novelty and of advantage.

40 The invention will be further illustrated by the following specific examples, the parts being by weight:

Reduction of o-nitranisol.

45 150 parts of o-nitranisol and 220 parts of benzene are charged into a suitable receptacle and brought to a boil under refluxing conditions; that is, with the use of a reflux condenser. The mixture is vigorously agitated and the reduction of the o-nitranisol is effected by the addition of zinc and caustic soda, making use of about 45 parts of caustic soda of 35 to 40° Bé. and about 200 parts of zinc dust. The zinc dust and caustic soda are advantageously added intermittently, adding one or the other at such a rate as to keep up a vigorous reflux action. The progress of the reaction can thus be regulated, and any large excess of either the zinc or caustic can be avoided, while insuring that sufficient of both are present for the continuation of the reaction at the appropriate rate, or as fast as is permitted by the reflux action. The completion of the reduction may require several hours, and will

vary with the amount of material treated, with the rate of addition, and with other conditions. The heating and agitation are continued for some time after the zinc and caustic have all been added, to insure completion of the reduction to the hydrazo stage. As the reduction becomes completed, the mass changes color very sharply to a light gray color. The reduction of the nitro compounds can be followed through the azoxy and the azo stages, and finally to the hydrazo stage.

At the end of the reduction, the benzene solution of hydrazanisol can be separated from the zinc residue and the zinc residue then extracted and washed with further amounts of benzene, or further amounts of benzene can be added directly to the reduction product, and substantially the entire amount of hydrazanisol extracted at once from the zinc residue. The residue can then be washed one or more times to complete the extraction of soluble matter therefrom, and the washed liquors so obtained can be used in the further carrying out of the process, by dissolving in them the further amounts of nitro compound to be reduced. The zinc residue can be freed from the adhearing solvent by distillation and can thus be obtained in a dried and isolated state, well adapted for special purposes without incineration or further treatment.

The benzene solution of hydrazanisol produced as above described, can be directly used for the conversion of the hydrazanisol to dianisidine; for example, in the manner described in the companion applications Serial Nos. 390,886 and 390,887, filed June 22, 1920. The hydrazanisol can also be separated from the benzene solution, for example, by crystallization on cooling, or by distillation of the benzene, and the hydrazanisol can thus be obtained in an isolated state.

Instead of using benzene as the solvent, toluene can be similarly used, although it is desirable to use a somewhat larger amount of toluene than of benzene in both the reduction and the extraction operation.

Reduction of nitrobenzene.

110 150 parts of nitro-benzene and 200 parts of benzene are mixed together in a suitable receptacle and heated to refluxing condition with a reflux condenser. The mixture is vigorously agitated and the nitro-benzene is then reduced to the hydrazobenzene by means of zinc and caustic soda using about 32 parts of caustic soda of 35 to 40° Bé., and about 200 parts of zinc dust. The zinc dust and caustic soda are added intermittently and in small portions, adding one or the other as needed at such a rate as to keep up a vigorous refluxing action. When all the zinc and caustic have been added, the heat-

ing is continued, with agitation, for a further period until the reduction is complete. Upon completion of reduction the yellow mass changes color very sharply to a light

5 gray.

- At the end of the reduction further amounts of benzene are added and the benzene solution of the hydrazobenzene is then separated from the zinc residue, the zinc residue washed with further amounts of benzene and the last traces of benzene removed from the zinc residue by distillation. The hydrazobenzene is thus obtained in solution, and the solution itself may be 15 used, for example, for rearrangement of the hydrazobenzene to benzidine or the hydrazobenzene can itself be separated from the solution by crystallization or by distillation of the benzene.
- 20 In a similar manner o-nitrotoluene can be reduced to hydrazotoluene and the hydrazotoluene obtained either in an isolated state, or directly in the form of a solution well adapted for treatment for the rearrangement 25 of the hydrazotoluene to tolidine.

In the process above described it will be noted that the amount of caustic soda used is only a small fraction of the amount theoretically required to convert the zinc into zincate. In Example 1, the amount of caustic soda used is about 6.4% to 7.9% of the weight of zinc used, or about 5.25% to 6.38% of the theoretical amount necessary to convert the zinc into sodium zincate. In 35 Example 2, the amount of caustic soda is about 4.6% to 5.5% of the weight of the zinc used, or about 3.75% to 4.53% of the amount theoretically required to convert the zinc into zincate. It will thus be seen that 40 the amount of caustic soda may vary from about 3.5% to 7% of the amount theoretically required to convert the zinc present into sodium zincate, and that zinc to the extent of more than about twelve (12) times that required to form sodium zincate with the 45 caustic soda will be present at the end of the reduction, mainly as zinc oxide or hydrated oxide, with the presence of only a very small amount of sodium zincate. This 50 materially facilitates the separation of the solution of hydrazo compound and results in giving a zinc oxide product directly usable for special purposes.

It is to be understood that the water of the caustic soda solution is a requisite in the process, since it furnishes the necessary hydrogen over and above the amount of hydrogen furnished by the relatively small amount of caustic soda used. In the course of the reaction of the zinc and caustic soda, while it is not definitely known, it seems that the zinc passes through the sodium zincate stage in producing the zinc oxide found in the zinc residue. Another theory is that the sodium zincate acts as a catalyst in the reaction.

The major portion of the reduction appears to be effected by the reaction between zinc and water, the reaction taking place in the presence of caustic soda.

In the claims the words "a few percent" 10 are to be construed broadly to embrace the limits 4.5% to 8%, referring to the weight of zinc used as previously set forth.

We claim:

1. The method of reducing a nitro compound, which comprises subjecting the nitro compound, in solution in an organic solvent immiscible with water, to the reducing action of zinc and caustic alkali, the amount of zinc being in excess of that required to form 75 sodium zincate with the caustic alkali.

2. The method of reducing a nitro compound to a hydrazo compound, which comprises subjecting the nitro compound, in solution in an organic solvent immiscible 80 with water, to the reducing action of zinc and caustic alkali until the hydrazo stage is reached, the amount of zinc being in excess of that required to form sodium zincate 85 with the caustic alkali.

3. The method of reducing o-nitranisol to hydrazanisol, which comprises subjecting the o-nitranisol to the reducing action of zinc and caustic alkali in the presence of an organic solvent immiscible with water, the 90 amount of zinc being in excess of that required to form sodium zincate with the 95 caustic alkali.

4. The method of producing and isolating a hydrazo compound, which comprises subjecting a nitro compound to reduction with zinc and caustic alkali in the presence of an organic solvent immiscible with water and thereby producing directly a solution 100 of hydrazo compound in the organic solvent, 105 and separating such solution from the zinc residue, the amount of zinc present being in excess of that required to form sodium zincate with the 110 caustic alkali.

5. The method of producing and isolating a hydrazo compound, which comprises subjecting a nitro compound to reduction with zinc and caustic alkali in the presence of an organic solvent immiscible with water, adding further amounts of the solvent at the end 115 of the reduction, and separating the solution of hydrazo compound from the zinc residue, the amount of zinc being in excess of that required to form sodium zincate with the 120 caustic alkali.

6. The method of reducing a nitro compound which comprises subjecting the nitro compound in solution in a solvent of the benzene series having a low boiling point to the reducing action of zinc and caustic alkali at about the boiling temperature of said solvent, the amount of zinc present being more about twelve times that required to form sodium zincate with the caustic alkali.

7. The method of reducing a nitro com- 125

ound to a hydrazo compound which comprises subjecting the nitro compound in solution in a solvent of the benzene series having a low boiling point to the reducing action of zinc and caustic alkali at approximately the boiling point of the solvent until the hydrazo stage is reached, the amount of zinc present being more than about twelve times that required to form sodium zincate with the caustic alkali.

8. The method of producing and isolating hydrazanisol, which comprises subjecting o-nitranisol to reduction with zinc and caustic alkali in the presence of a solvent of the benzene series having a low boiling point, and extracting the hydrazanisol from the zinc residue in the form of a solution in such solvent, the zinc and caustic being added in such proportions as to produce zinc oxide in the mixture after the reaction has taken place.

9. The method of reducing a nitro compound, which comprises subjecting the nitro compound in benzene solution to the action of zinc in the presence of aqueous caustic alkali, the amount of caustic alkali being only a few percent of the amount required to convert the zinc into zincate.

10. The method of producing hydrazanisol, which comprises subjecting about 150 parts of o-nitranisol and 220 parts of benzene to the action of about 45 parts of caustic soda of 36 to 40° B. and about 200 parts of zinc dust at the boiling point of the benzene, separating the benzene from the hydrazo compound formed, and treating the zinc residue with further amounts of benzene until soluble admixtures are removed, thereby leaving the zinc residue substantially free from soluble admixtures.

11. The method of producing hydrazanisol, which comprises subjecting about 150 parts of o-nitranisol and 220 parts of benzene to the action of about 45 parts of caustic soda of 35 to 40° B. and about 200 parts of zinc dust at the boiling point of the benzene, the zinc and caustic soda being added intermittently in small portions, separating the benzene from the hydrazo compound formed, and treating the zinc residue with further amounts of benzene until soluble admixtures are removed, thereby leaving the zinc residue substantially free from soluble admixtures.

12. A process for the reduction of a nitro compound of the aromatic series, which comprises acting on the nitro compound with zinc and caustic alkali in the presence of an organic solvent immiscible with water, the amount of caustic alkali being only a few percent of the amount required to convert the zinc into zincate.

13. A process for the reduction of o-nitranisol to produce hydrazanisol, which comprises acting on the o-nitranisol with

zinc and caustic alkali in the present of a liquid organic solvent immiscible with water, the amount of caustic alkali being only a few percent of the amount required to convert to zinc into zincate.

14. The method of reducing a mono-nitro compound, which comprises subjecting the mono-nitro compound, in solution in an organic solvent immiscible with water, to the reducing action of zinc and caustic alkali, the amount of zinc being in excess of that required to form sodium zincate with the caustic alkali.

15. A process for reducing a mono-nitro compound of the benzene series, which comprises subjecting the nitro compound in the presence of an organic solvent immiscible with water to the action of zinc and a solution of caustic alkali containing an amount of caustic alkali of about 3.5 to 7 per cent of the amount required to convert the zinc into zincate.

16. A process for reducing a mono-nitro compound of the benzene series, which comprises subjecting the nitro compound in the presence of a low boiling hydrocarbon of the benzene series to the action of zinc and a solution of caustic alkali in water containing an amount of caustic alkali of about 3.5 to 7 percent of the amount required to convert the zinc into zincate.

17. A process for the reduction of a mono-nitro compound of the benzene series, which comprises subjecting the nitro compound, in the presence of an organic solvent immiscible with water, to the action of zinc and a solution of caustic alkali in water containing an amount of caustic alkali of about 3.5 to 7 percent of the amount required to convert the zinc into zincate, the zinc being added to the rest of the ingredients in small portions intermittently.

18. A process for the reduction of o-nitranisol to hydrazanisol, which comprises subjecting the o-nitranisol, in the presence of boiling benzene, to the action of zinc and a solution of caustic alkali, the amount of caustic alkali being about 3.5 to 7 percent of the amount required to convert the zinc into zincate.

19. A process for the reduction of o-nitranisol to hydrazanisol, which comprises subjecting the o-nitranisol, in the presence of boiling benzene, to the action of zinc and a solution of caustic alkali in water containing an amount of caustic alkali of about 3.5 to 7 percent of the amount required to convert zinc into zincate, the zinc being added to the rest of the ingredients in small portions intermittently.

In testimony whereof we affix our signatures.

RALPH. A. NELSON.
